UNITED STATES PATENT OFFICE.

JOSEPH COLIN, OF AVA, ILLINOIS.

RAIL-JOINT.

SPECIFICATION forming part of Letters Patent No. 761,660, dated June 7, 1904.

Application filed March 5, 1904. Serial No. 196,725. (No model.)

To all whom it may concern:

Be it known that I, JOSEPH COLIN, a citizen of the United States, residing at Ava, in the county of Jackson and State of Illinois, have 5 invented certain new and useful Improvements in Rail-Joints, of which the following is a specification.

This invention relates to novel improvements in rail-joint structures; and one of the 10 objects of the invention is to provide a continuous bearing at the point of jointure of the meeting ends of the rails to obviate the rounding thereof due to the continued use thereof and wear caused by the rolling-stock passing 15 thereover.

A further object of the invention is to increase the general rigidity of the joints, and for the above purpose the rails are of a special form, adapted for coöperation with a specially- 20 devised joint member by which same are connected.

For a full description of the invention and the merits thereof and also to acquire a knowledge of the details of construction of the 25 means for effecting the result reference is to be had to the following description and accompanying drawings.

While the essential and characteristic features of the invention are susceptible of modification, still the preferred embodiment of the 30 invention is illustrated in the accompanying drawings, in which—

Figure 1 is a perspective view showing the embodiment of the invention. Fig. 2 is a 35 longitudinal vertical sectional view through the rail-joint. Fig. 3 is a vertical transverse sectional view. Fig. 4 is a detail perspective view of the joint member connecting the rails, showing the adjacent rail ends spaced there- 40 from.

Corresponding and like parts are referred to in the following description and indicated in all the views of the drawings by the same reference characters.

In the drawings the rails are designated 1, and same comprise a head or ball 2, spaced webs 3, and basal flanges 4. The spaced webs 3 of the rails diverge toward the basal flanges 4, and thereby form a continuous groove extending longitudinally of the underside of the

said rails. Because of the divergent relation of the spaced webs 3 the grooved portion 5 of each rail is of approximately triangular form, narrowing toward the upper portion thereof, as will be readily seen by reference to Figs. 1, 55 3, and 4. Each of the adjacent rails 1 is provided with an extension 6, projected from the head portion 2 thereof, which extension is received by a mortise or recess 7 in the corresponding portion of the adjacent rail end. The 60 extension 6 being at the point of jointure of the rail ends is the means whereby a continuous bearing-surface at this point is secured. The jar and vibration consequent to the employment of the common type of rail is thus 65 obviated.

The means for joining or securing the meeting ends of the rails together consists of a joint member 8, which is of wedge form in cross-section and which virtually constitutes 70 a wedge block. The joint member 8 is disposed within the grooved portion 5 at the adjacent end portions of the rails 1, and since this member is of wedge form, as set forth above, the same corresponds somewhat to the 75 form of the grooved portion 5, as will be appreciated. The joint member 8 is provided with lateral openings 9, through which fastening-bolts 10 or the like pass, said bolts also passing through corresponding openings 80 formed in the web portions 3 of the rail ends. Projected upwardly from the upper end portions of the joint member 8 are locking projections 11, which are received by recesses 12, formed in the ends of the rails, extending from 85 the grooved portions thereof into the head portions of same. The projections 11 constitute interlocking means between the rails, which greatly reinforces the connection and subserves the rigidity thereof to a maximum de- 90 gree. The projections 11 also coöperate, of course, with the fastening-bolts 10 to secure the rail ends together. The wedge form of the joint member 8 is essentially advanta- 95 geous in that the rail ends are centered in the relative disposition when receiving the pressure of the rolling-stock passing thereover. The wedge action thus obtained reduces the vibration in a manner apparent. The flanged basal portions 4 of the rail ends may be prop- 100

erly secured to the adjacent ties in the practical use of the invention.

Having thus described the invention, what is claimed as new is—

- 5 1. In a rail-joint, the combination of rails having the meeting end portions thereof provided upon the under sides with longitudinal grooves, a joint member disposed beneath the rails and received by the grooved portions thereof, projections extending upward from the end portions of the joint member and interlocking with the rail ends, and transverse fastenings passed through the rail ends and the joint member securing same.
- 10 2. In a rail-joint, the combination of rails having diverged web portions providing a wedge-shaped groove upon the under side

thereof, a wedge-shaped joint member disposed beneath the end portions of the rails within the wedge-shaped grooved portions 20 thereof, projections extended upwardly from the end portions of the wedge-shaped joint member, the rails being provided with recesses to receive the projections aforesaid, and transverse fastenings passed through the 25 rail ends and the joint member securing same together.

In testimony whereof I affix my signature in presence of two witnesses.

JOSEPH COLIN. [L. S.]
